[57] CLAIM

The ornamental design for a self storing security storm door, as shown and described.

DESCRIPTION

FIG. 1 is a front elevational view of a self storing security storm door showing my new design;

FIG. 2 is a rear elevational view thereof;

FIG. 3 is a right side elevational view thereof, the left side elevational view being a mirror image thereof;

FIG. 4 is a top plan view thereof;

FIG. 5 is a bottom plan view thereof;

FIG. 6 is a front elevational view of a modification of a self storing security storm door showing my new design;

FIG. 7 is a rear elevational view of the modification of FIG. 6.

FIG. 8 is a right side elevational view of the modification of FIG. 6, the left side elevational view being a mirror image thereof;

FIG. 9 is a top plan view of the modification of FIG. 6;

FIG. 10 is a bottom plan view of the modification of FIG. 6;

FIG. 11 is a front elevational view of another modification of a self storing security storm door showing my new design;

FIG. 12 is a rear elevational view of the modification of FIG. 11;

FIG. 13 is a right side elevational view of the modification of FIG. 11, the left side elevational view being a mirror image thereof;

FIG. 14 is a top plan view of the modification of FIG. 11; and

FIG. 15 is a bottom plan view of the modification of FIG. 11.

FIG. 8

FIG. 7

FIG. 10

FIG. 9

FIG. 6
